UNITED STATES PATENT OFFICE.

CHATTIN BRADWAY, OF SCHENECTADY, NEW YORK, ASSIGNOR TO GENERAL ELECTRIC COMPANY, A CORPORATION OF NEW YORK.

NOZZLE FOR ELASTIC-FLUID TURBINES.

No. 814,426.

Specification of Letters Patent.

Patented March 6, 1906.

Application filed May 19, 1905. Serial No. 261,150.

To all whom it may concern:

Be it known that I, CHATTIN BRADWAY, a citizen of the United States, residing at Schenectady, county of Schenectady, State of New York, have invented certain new and useful Improvements in Nozzles for Elastic-Fluid Turbines, of which the following is a specification.

The present invention relates to nozzles for elastic-fluid turbines, and relates, primarily, to those of a built-up type. In nozzles of this class as heretofore proposed the individual parts are expensive to make because of the amount of machine-work involved and the subsequent finishing by hand. Furthermore, the parts of the turbine in which the nozzles are supported require also to be accurately machined in order that the parts may be properly fitted in place, thus materially contributing to the cost of the nozzle.

The objects of the invention are, first, to simplify and cheapen the construction by making the nozzles wholly or largely of punched or stamped sheet-metal plates, thereby obviating any machine-work and also hand-finishing wholly or in large part; second, to provide nozzles of this character whose parts are so assembled as to form unitary structures which can be arranged in the nozzle-receiving openings of the supporting members of the turbine without requiring the walls of the openings to be machined and which can be readily interchanged or renewed if such is desirable.

For an understanding of the details of construction attention is directed to the following description and of the features of novelty to the claims appended hereto.

40 In the accompanying drawings, which illustrate certain embodiments of the invention, Figure 1 is a plan view of a nozzle of the sectionalized type and its support. Fig. 2 is a longitudinal section of a nozzle. Fig. 3 is a 45 section through the bowl or chamber portion of a nozzle. Fig. 4 is a view of one of the side plates. Fig. 5 is a detail perspective view of one of the partitions of a nozzle drawn on an enlarged scale. Fig. 6 is a longitudinal section of a modified form of nozzle with portions broken away. Fig. 7 is a plan view thereof. Fig. 8 is a transverse section on line 8-8, Fig. 6; and Fig. 9 is a similar section of an alternative form of nozzle.

The parts of the nozzle are made of some homogeneous sheet metal of a suitable gage and which may with advantage be polished in sheet form before the parts are cut therefrom, thus rendering the process simpler. With such commercial metal as cold-rolled steel or other smooth metal the sheets may be satisfactory without polishing. As a general proposition, however, polishing is desirable, as it reduces surface-friction of the motive fluid in passing through the nozzle-passages, and thereby increases the efficiency.

Referring to the drawings, 1 is a portion of a turbine, which for the purpose of illustration represents a diaphragm that is adapted to support a nozzle 2 or a larger number, if desired. Obviously any suitable portion or portions of the turbine may be employed to carry the nozzles. The diaphragm or support is provided with one or more segmental openings, preferably cored out in the same to the desired size and shape so as to receive the nozzles. The walls of the opening may be left in the rough, as the nozzles completely line them and form the walls for guiding and directing the passage of motive fluid. The nozzles may be arranged in the support to cover only a limited arc of the bucket-wheels or may extend entirely around the same, as desired.

The nozzle comprises two sections—viz., 85 a distributing-chamber portion formed by the supporting-plate 3 and a discharge portion 4, having one or more discharge-passages 5. The first portion serves to support the discharge portion, although it may be dispensed with in some embodiments. It preferably takes the form of a segmental plate slightly larger than the dimensions of the nozzle-receiving openings in the support or diaphragm, so as to provide a circumferential flange 6 for receiving the bolts 7, which secure the nozzle in place. The segmental plate is provided with a longitudinal opening corresponding substantially to the opening in the support and communicates with the discharge-passages 5 and is provided with a chamber, bowl, or depression 8, whose walls incline toward the opening thereof. This portion 8 serves as a distributing-chamber, which collects the motive fluid from the steam-chest or preceding wheel-buckets, as the case may be, and delivers it to the discharge-passages. The plate may,

however, be made without the chamber, in which case it serves simply to support the discharge portion 4 in the diaphragm.

The discharge portion of the nozzle comprises two preferably integral sheet-metal side plates 9, arranged concentrically on a curvature corresponding to that of the wheel-buckets and also with that of the opening in the segmental plate. Between the side plates are suitably secured partitions 10, which guide and direct the passage of the motive fluid, as do also the side plates. When two partitions are employed, they form with the side plates a single section or passage 15 nozzle, and when a larger number are employed they constitute with the side plates a plurality of individual fluid-discharging passages or what is termed a "sectionalized" nozzle. The partitions may be cast, forged, 20 or otherwise suitably formed pieces and of any desired shape to produce expanding or non-expanding passages. In the present instance the partitions 10 are made of sheet metal of good substantial gage and punched 25 therefrom to the required size. The punchings are curved on a form or in a bending-machine, so that when assembled each adjacent pair constitutes the end walls of an individual discharge-passage. As the partitions 30 are correspondingly shaped and similarly disposed, the fluid-discharging passages formed by them each comprises a suitable receiving end, which communicates with the distributing-chamber 8 of the section 3, and 35 a discharge end, which is more or less inclined to the plane of the bucket-wheel to deliver the motive fluid at the proper angle against the buckets. The side plates and partitions are secured together by riveting. As a simple 40 manner of doing this each partition is punched with integral lugs 11, Fig. 5, at their side edges. These are adapted to engage and rivet in correspondingly-shaped perforations 12, which are punched out in the side 45 plates 9. The longitudinal edges of the opening of the supporting-plate 3 are turned down at right angles during the stamping operation, so as to form securing-flanges 13, to which the discharge portion of the nozzle is 50 attached. These flanges and also the side plates at their upper edges have registering openings or perforations 14 punched in them to receive the securing-rivets 15. The side plates are fitted between the flanges, so that 55 smooth unbroken surfaces are obtained in the passages 5. The perforations 14 of the plates are countersunk, so that the rivet may be flush with the inner walls of the passages, as shown in Fig. 9. After the parts are 60 punched and shaped the partitions and side plates are first assembled and the lugs 11 riveted, thus forming the discharge portion 65 complete. This latter is next assembled in the supporting-plate and riveted thereto. To mount the nozzle in the diaphragm or

support 1 the upper surface thereof is first turned off true and holes bored and tapped around the segmental opening therein to receive the securing-bolts 7, by which the nozzle is held in place. It may be advantageous to enlarge or slot the perforations in the supporting-plates through which the bolts 7 pass, so that slight adjustment may be possible to obtain the proper relation between the discharge ends of the passages and the buckets.

Referring to Figs. 6 and 7, the supporting member 16 is provided with a bowl 17 for each discharge-passage 18. The metal punched out to make the opening or throat 19 between the bowl and the discharge-passage is turned down to form securing-lugs 20, to which the side plates are riveted. In this construction the passages are made expanding toward the discharge end by means of sheet-metal partitions 21, made in two parts to constitute a wedge, as shown in Fig. 6. The partitions need not necessarily be made in two parts, as a single piece may be employed and formed into the wedge. In this modification the side walls of the passage may be diverging, as shown in Fig. 8, or parallel, as shown in Fig. 9. When diverging side walls are employed, as in the modification, the passages are expanding in both directions.

The nozzle which I have illustrated is of a sectionalized type; but it is within the scope of the invention to construct single-passage nozzles on the same principle. Furthermore, while I have described the side members of a nozzle as having perforations to receive the lugs on the partitions, they may be stamped with grooves or slots to receive the edges of the partitions or the grooves may be milled in the side plates before the latter are curved or given their final form. Also the side members may be arc-shaped castings carefully finished on the surfaces which serve as the walls of the fluid-discharging passages and the partitions secured to them in any suitable manner.

In accordance with the provisions of the patent statutes I have described the principle of operation of my invention, together with the apparatus which I now consider to represent the best embodiment thereof; but I desire to have it understood that the apparatus shown is only illustrative and that the invention can be carried out by other means.

What I claim as new, and desire to secure by Letters Patent of the United States, is—

1. An interchangeable nozzle for elastic-fluid turbines, comprising a fluid-discharging conduit or passage whose fluid guiding and directing walls consist of separately-formed sheet-metal pieces.

2. A nozzle for elastic-fluid turbines, comprising a fluid-discharging conduit or passage whose fluid guiding and directing walls con-

- sist of separately-formed sheet-metal pieces, and means for securing the pieces together.
3. As an article of manufacture, a nozzle for an elastic-fluid turbine, comprising independent and concentrically-curved side walls, and transversely-arranged partitions which unite the side walls and with the latter form fluid-discharging passages.
4. A nozzle for elastic-fluid turbines, comprising sheet-metal end and side walls which guide and direct the passage of motive fluid, means for securing the walls together, and a supporting-plate for the said walls by which the nozzle is mounted in the turbine.
5. A nozzle for elastic-fluid turbines, comprising a section having one or more fluid-discharging passages, and a sheet-metal section provided with a chamber which collects and delivers the motive fluid to the discharging passage or passages, and means for securing the sections together to form a unitary structure.
6. A sheet-metal nozzle for elastic-fluid turbines, comprising curved side plates, partitions secured between them which form one or more fluid-discharging passages, a supporting member, integral securing-flanges provided on the supporting member, and means for securing the side plates to the flanges.
7. A sheet-metal nozzle for elastic-fluid turbines, comprising curved side plates, partitions secured between them which form one or more fluid-discharging passages, a sheet-metal supporting member provided with an opening, depressed walls adjacent the opening which form a chamber for collecting and
- delivering the motive fluid to the discharge passage or passages, and integral flanges formed on the supporting member at the edges of the opening for supporting the side plates.
8. A nozzle for elastic-fluid turbines comprising two independent and parallel side members, and partitions rigidly secured between the members to constitute a plurality of closely-associated fluid-discharging passages, in combination with a diaphragm or other support to which the nozzle is removably secured.
9. The combination of a diaphragm or other support having an arc-shaped slot or opening, and a nozzle corresponding in shape to the slot or opening and removably fitted therein, said nozzle comprising arc-shaped side plates; and transversely-arranged partitions which are secured to the side plates and coöperate therewith to form a plurality of closely-associated passages having the same angle of discharge.
10. As an article of manufacture, a distributing-chamber for a nozzle, comprising a sheet-metal plate formed with one or more dished or bowl-shaped portions which serve to collect and deliver the motive fluid to the discharge passage or passages of the nozzle.
- In witness whereof I have hereunto set my hand this 17th day of May, 1905.

CHATTIN BRADWAY.
